UNITED STATES PATENT OFFICE.

CHARLES W. MILLS, OF SYRACUSE, NEW YORK.

AUTOMATIC WATER HEATER.

Application filed October 25, 1922. Serial No. 596,852.

To all whom it may concern:

Be it known that I, CHARLES W. MILLS, a citizen of the United States, residing at Syracuse, in the county of Onondaga and State of New York, have invented certain new and useful Improvements in Automatic Water Heaters, of which the following is a specification.

This invention relates to automatic water heaters, and has for its object to provide a novel, simple and instantaneous water-heating device, which may be installed adjacent a sink, lavatory, bath-tub, or at any other point where it is desired to draw and use hot-water. A further object is to provide a heating apparatus comprising a cylindrical heating element or fluid fuel burner, which is disposed concentrically in an annular drum that is arranged to contain a relatively thin body of water, the said heating element being supplied with combustible gas, whose delivery is regulated entirely by the volume of the water which flows through the apparatus when the hot-water faucet is opened. A further object is to provide novel means for automatically igniting the gas supplied to the heating element. A further object is to provide tension means which co-operates with the normal cold water pressure for automatically shutting off the supply of the gas to the burner, whenever the hot-water faucet is closed.

I attain these objects by the means set forth in the detailed description which follows, and as illustrated by the accompanying drawings, in which—

Figure 1 is a central vertical longitudinal section, taken on line 1—1 of Fig. 2; showing the water and gas valves closed. Fig. 2 is a top-plan view of the device. Fig. 3 is a fragmentary section, also taken on line 1—1 of Fig. 2; showing the water and gas valves open. Fig. 4 is a vertical cross-section taken on line 4—4 of Fig. 3 with the valve omitted. Fig. 5 is a similar section, taken on line 5—5 of Fig. 3. And Fig. 6 is a horizontal section, taken on line 6—6 of Fig. 1.

In the drawings, 2 represents the cold water supply pipe, which connects by a gland-nut 2' with a cold water fitting 3, the latter having a lateral branch 3', which conducts the cold water to the annular drum 4, to which it is connected by a gland-nut 3''. The fitting 3 is provided with a hollow cylindrical portion 3'', which aligns axially with the pipe 2, and comprises a valve

chamber 3'', in which a valve 5 plays. The chamber 3'' receives the water from the pipe 2 through a by-pass 3'', and the chamber 3'' discharges the cold water into the branch 3' through a by-pass 3''. The valve 5 controls the flow of the larger volume of the cold water from the pipe 2 towards the drum 4. During the intervals in which no hot water is being drawn from the heater, the valve 5 is positioned, as shown in Fig. 1, and prevents the cold water from passing directly from the pipe 2 into the branch 3''. By this construction and arrangement of the parts, the cold water must flow through the by-pass 3'' to the chamber 3'', and thence through the by-pass 3'' in order to reach the branch 3' and the drum 4. The chamber 3'' being larger than the valve-opening 3'', the filling of the said chamber tends to force and hold the valve 5 in the closed position, shown in Fig. 1. 6 represents the hot-water outlet, to which the usual hot water faucet (not shown) may be attached, and by means of which the hot water may be drawn off from the drum 4. The opening of the hot water faucet induces a greater flow of the cold water from the pipe 2 into the fitting 3, than the by-passes 3''—3'' can carry, and therefore the valve 5 is moved towards the right, as shown in Fig. 3, for opening the main passage from the pipe 2 into the branch 3''. This movement of the valve 5 being effected by the full cold water pressure, readily and quickly empties the chamber 3'', by forcing the water contained therein through the by-pass 3'', which may be readily effected, since the opening of the hot water faucet instantly reduces the pressure in the drum 4, and thereby induces a flow that exceeds the capacity of the said by-passes. This opening of the valve 5 is quickened and rendered more positive by reason of the cupping of the said valve, as at 5', in a well-known manner.

The drum 4 is substantially cylindrical, and its opposite ends are open and externally threaded for facilitating the attachment of similar annular caps 4''—4'', which are provided with threaded flanges 4''' for the purpose. These caps are also provided with similar flanges 4'' adjacent their inner circumferences the latter flanges serving as annular abutments for a concentric cylinder 7, which together with the drum 4 forms a relatively thin or shallow water chamber 7''. The cylinder 7 is preferably made of rela-

tively thin gauge metal for offering the least resistance to the heating of the water, and its opposite ends are provided with similar outwardly projecting annular flanges 7^a, 5 which snugly engage the inner faces of the caps 4^a—4^b, for effecting adequate water seals at said points. The interior of the drum 7 comprises the combustion chamber 7^b of the heater, and within this chamber is 10 concentrically disposed a hollow cylindrical heating element or burner 8, which is considerably smaller in diameter than the drum 7, as well as the openings in the caps 4^a—4^b, and its entire circumference is perforated, 15 as at 8', for the "jetting" of the combustible gas, by which the water in the chamber 7' is heated. The ends of the burner are preferably closed, as shown, for preventing the escape of the gas except through the perforations. The top end 8^a is preferably provided 20 with a scalloped flange 8^c, the latter being perforated to receive bolts 8^d, which are threaded into the cap 4^a, as best seen in Figs. 1 and 2. The lower end 8^b of the 25 burner has a central gas opening 8^e and said end is also provided with threaded openings to receive bolts 9', by which a branch 9^a of a gas-fitting 9 is rigidly secured to the burner. The body of the fitting 9, whose axis aligns 30 with that of the portion 3^b of the fitting 3, is provided with a common gas chamber 9^b, which is constantly supplied with gas from a pipe 10. The gas chamber 9^b adjacent the branch 9^a is formed with a seat for the main 35 gas valve 12, which controls the intermittent flow of the gas from the chamber 9^b towards the burner 8. The valve 12 is mounted on a stem 12', which projects into the valve chamber 9^c, and in which chamber 40 is disposed a cushion spring 13, whose tension tends to yieldingly hold the valve 12 in its seat. For convenience in assembling the valve 12, the body 9 is provided with a screw-plug 9^d. The opposite end of the gas 45 chamber 9^b is formed with a smaller seat for the pilot light valve 14, the latter being rigid on a stem 14', which aligns axially with the stem 12' and the valve 5. A coil spring 14^a is disposed between the valve 14 and the inner end of the stem 12', and exerts 50 its tension for seating the valve 14. The normal tension of the spring 14^a is not strong enough to unseat the valve 12. 9^e represents an arm of the fitting 9, whose free 55 end is formed with a cup 15, for shielding a constantly burning pilot light 15, which is supplied with gas by means of a relatively small normally open duct 15^a, which taps the gas chamber 9^b. The flow of the gas through 60 the duct 15^a is regulated by a screw 15^b. By this construction and arrangement the pilot light receives the gas notwithstanding the positions of the valves 12 and 14. The stem 14' of the valve 14 passes through a bore 65 14^b, and a portion of said stem is reduced to form a gas chamber 14^c which is filled with the gas whenever the valve 14 is unseated. From the chamber 14^c the gas then flows through a duct 14^d which delivers the gas to the duct 15^a beyond the valve 15^b. 70 This extra supply of the gas causes the pilot light to flash and extend beyond the cup 15^a into the combustion chamber 7^b, for igniting the gas which may escape through the perforations of the burner 8, following the 75 opening of the valve 12. The enlargement of the pilot frame, however, is only momentary for the normal diameter portion of the stem 14' continues to move to the right in Figure 1 until it completely crosses the lower 80 end of the duct 14^d and closes the same to the flow of gas therethrough. Consequently, the augmented flow of gas to the pilot burner occurs only from the initial unseating of valve 14 until the adjacent reduced portion 85 of the valve stem moves entirely across the lower end of the duct 14^d, when the enlarged flow is reduced to the normal flow through the passage 15^a. The remote or left end 90 of the stem 14' continues through the fitting 9 and projects into the valve chamber 3^d, at which point the said stem is fitted with an adjusting screw 14^e, which is employed for varying the strokes of the stems 14' and 12', when the stem 14' is engaged and driven 95 towards the right by the opening of the valve 5. The gas-fitting is provided with a flange 9^f which is bolted to a corresponding flange of the fitting 3^b, and the flange 9^f serves as a closure for the valve chamber 3^d as shown 100 in Figs. 1 and 3. The scallops 8^c are arranged to provide a number of slight openings 4^e for the escape of the waste products 105 of combustion from the chamber 7^b. 110 The operation of my improved water heater, which is extremely simple, is as follows: Assuming that the apparatus is connected up, and that the various parts are in the positions shown in Fig. 1, the opening of the hot-water faucet for drawing the hot-water from the drum 4, instantly effects the opening of the valve 5, moving the same from the position shown in Fig. 1 to that shown in Fig. 3. This diverts the cold water 115 from the pipe 2 directly into the branch 3^b, and empties the chamber 3^d. At the same time the valve 5 engages and moves the stem 14' in the direction for opening the valve 14. The opening of the latter valve increases the supply of the gas to the pilot light 15, and also effects the unseating of the gas valve 12 through the engagement of the stem 14' with the stem 12'. This allows the 120 gas to flow from the chamber 9^b to the burner 8, where it is instantly ignited by the enlarged pilot light 15. It will be noted that the valve 14 has a limited movement prior to engaging valve stem 12' so that the pilot flame is enlarged just previous to the flow 125 of gas to the burner so that when the main 130

flow does begin the pilot light is of proper size to instantly ignite it. The first water drawn from the drum will be cold. But within a few seconds warm, and then hot 5 water will be obtainable in a steady stream. The temperature of the water may be varied by partially opening and closing the outlet 6, in a well-known manner. The shutting off of the hot water faucet, stops the flow 10 of the water through the branch 3' and the drum 4, and relieves the pressure upon the valve 5 to such extent that the said valve will be closed after a short interval (see Fig. 1), by the refilling of the chamber 3⁴, 15 as explained. As soon as the flow of the water through the heater is stopped, and the pressure against the valve 5 is relaxed, as described, the springs 13 and 14^a effect the closing of the valves 12 and 14 and also 20 partially return the valve 5 to its closed position. The closing of the valve 14 re-establishes the normal feed of the gas to the pilot light 15, as explained.

Having thus described my invention, what 25 I claim, is—

1. A water heater including a water chamber having inlet and outlet openings, a burner for heating the chamber, a valve for supplying gas to the burner, a pilot light 30 for igniting the gas at the burner, a valve having movement independent of the first valve for increasing the normal feed of the gas to said light prior to actuation of said first valve, a valve for controlling the flow 35 of water to the chamber, a by-pass structure for supplying water to the chamber while the heater is idle, means actuated by the opening of the water-control valve for successively opening the pilot light valve and the gas burner valve, and means for closing 40 the gas-control valves and for starting the closing of the water-control valve upon stopping the flow of water through the chamber.

2. In a water heater, a chamber having a 45 cold-water inlet and a hot-water outlet, a burner for heating the chamber, a cold-water pipe and a fitting having a branch for conducting cold water to the chamber connected to said pipe, a valve carried by said fitting 50 for controlling the flow of the cold water directly into said branch, a valve for controlling the flow of gas to said burner, a pilot light adapted to ignite the gas in the burner, a valve for controlling a part of the 55 flow of the gas to the pilot light, means actuated by the opening of the water-control valve for sequentially opening the pilot light valve and the gas burner valve, and means for closing the last two valves and for partially closing the water-control valve.

3. In a water heater, a water chamber 60 having a cold-water inlet and a hot-water outlet, a burner for the chamber, a cold-water pipe and a fitting connected thereto, said fitting having a branch for conducting

the cold water towards the inlet of the chamber, a valve carried by said fitting for controlling the flow of cold water directly into said branch, means operable by the valve, on opening, for supplying fuel to the burner, and a valve chamber for the valve in said fitting, said chamber connected to said cold water pipe and to said branch by a by-pass adapted to supply water to the chamber and said branch, the water entering through the by-pass behind the valve to hold said valve in closed position while said outlet 70 remains closed. 75

4. In a water heater, a water chamber having inlet and outlet ports, a burner for heating the chamber, a valve for supplying gas to the burner, a pilot light for igniting the gas at the burner, a valve for increasing momentarily the flow of gas to the pilot light, a connection between the valves permitting of slight initial or prior actuation of the pilot light valve relative to the gas burner valve, means including said connection for closing the valves, and means operable by the pressure of water flowing to the 80 chamber for opening the two valves in order. 85

5. In a water heater, a water chamber having a cold water inlet and a hot water outlet, a cylindrical burner for heating the chamber, a valve for supplying fuel gas to said burner, a pilot light adapted to ignite the gas in the burner, a valve for controlling the gas to said light, a cold water fitting and a cold water pipe connected thereto, said fitting having a branch for conducting the cold water to the inlet opening of the chamber, a valve carried by said fitting for controlling the flow of cold water through said branch, means actuated by the opening of said cold-water valve for sequentially opening the pilot light valve and the fuel-gas valve, and means for closing the gas valves and for partially closing the water valve when the flow of water through the 95 chamber is arrested. 100

6. In a water heater, a water chamber having inlet and outlet ports, a burner for heating the chamber, a spring-seated valve for controlling the flow of gas to the burner, a pilot light for igniting the gas at the burner, a valve for controlling and momentarily increasing the flow of gas to the pilot light, said valve for the pilot light when opening acting also to open the gas burner valve, said pilot light valve being slightly spaced 115 from the latter to permit prior actuation to a limited extent, a spring interposed between the two valves for seating the pilot light valve as the spring of the gas burner valve seats the latter, and means operable by the pressure of water flowing to the chamber for effecting an unseating of the pilot light valve and the gas burner valve. 120

7. In a water heater, a water supply pipe having an offset cylindrical chamber open- 130

ing thereinto through a reduced opening, said chamber having its remote end communicatively connected to the supply pipe on opposite sides of said chamber, a plunger-like valve operable in the cylindrical chamber and having a stem portion slid able through the reduced opening, and means ex-

tending into said remote end and engageable by the valve to be operated thereby for supplying heat to the water flowing through 10 said pipe.

In testimony whereof I affix my signature.

CHARLES W. MILLS.
